UNITED STATES PATENT OFFICE.

FRANK K. WADE, OF PATERSON, NEW JERSEY, ASSIGNOR OF ONE-HALF TO R. C. DENNY, OF BLOOMFIELD, NEW JERSEY.

AUTOMATIC TRAIN-STOP.

1,136,567.

Specification of Letters Patent. Patented Apr. 20, 1915.

Application filed January 30, 1913. Serial No. 745,116.

To all whom it may concern:

Be it known that I, FRANK K. WADE, a citizen of the United States, and a resident of Paterson, in the county of Passaic and 5 State of New Jersey, have made certain new and useful Improvements in Automatic Train-Stops, of which the following is a specification.

My invention relates to devices for automatically stopping railroad trains when the latter run by signals set at danger against them, and it consists in the combinations, constructions, and arrangements herein described and claimed.

15 An object of my invention is to provide a simple arrangement of electric devices on each engine which may be operated by means of circuits completed by a series of third rails or short conductors disposed along the 20 track.

A further object of my invention is to provide means operated by the electrical devices for operating the air brakes and for shutting off the steam supply.

25 A further object of my invention is to provide means which may be operated by the movement of the railway track signals or semaphores as they are being shifted into their indicating positions for grounding the 30 third rail sections.

A further object of my invention is to provide means for recording the time at which the train is automatically stopped and at which it is again started.

35 Other objects and advantages will appear in the following specification and the novel features of the device will be particularly pointed out in the appended claims.

My invention is illustrated in the accompanying drawings forming part of this application in which—

Figure 1 is a diagrammatic view of the mechanism on the engine and of the third rail and its associated track signal, the latter being at "clear", Fig. 2 is a view similar to that shown in Fig. 1 showing the parts in a different position, the signal being at "danger", Fig. 3 is a diagrammatic view of a modified form of the switch actuating 50 means, and Fig. 4 is a diagrammatic view showing the arrangement of the third rail conductors and their associated signaling devices.

In carrying out my invention I make use 55 of a pressure line 1 which may be connected

with a pressure tank 2, the latter being either the main air reservoir or a steam chest or similar reservoir for motive fluid. This line connects with a valve casing 3 in which is disposed a valve 4 whose stem 5 is connected 60 with the armature 6 of a magnet or solenoid 7. The valve is provided with an opening 8 arranged to be brought into alinement with the pipes 1 and 9. The movement of the valve 4 is designed to cut off communication 65 between the pipes 1 and 9 and to establish communication between the pipe 9 and the interior of the valve casing through a groove 4*. Openings 3* in the valve casing permit the escape of air or steam into the atmosphere. While I have described this motive fluid control device in detail it will be understood that this description is merely for the purpose of making the operation clear and that any suitable mechanism might be 70 used in lieu of that shown for establishing communication between the pipes 1 and 9 in one position of the armature 6 and for cutting off communication between the pipes and for connecting the pipe 9 with the outer 75 atmosphere when the armature 6 is in another position.

At 10 I have shown a cylinder having a piston 11, these parts being such as are found in the ordinary Westinghouse air 80 brake. As long as pressure is supplied to the pipe 9 the piston 11 is forced inwardly against the spring 12 so as to permit the brakes to be released from the wheels in the ordinary manner.

90 A cylinder 13 which is similar to the cylinder 10 has a piston 14 which is acted on by a spring 15. Connected with the cylinder 14 is the valve stem 16 of a valve 17 disposed in a valve casing 18 which forms 95 part of the steam pipe line 19 leading to the throttle (not shown). As long as there is sufficient pressure in the pipe 9 the valve 17 will be held open as shown in Fig. 1, thereby permitting a passage of steam, but 100 when the pressure goes off from the line 9 the spring 15 will seat the valve 17 so as to prevent the passage of steam to the throttle.

On each engine is disposed the solenoid or magnet 7 mentioned above and the magnets 20, 21, 22 and 23. At 24 I have shown diagrammatically a recording device having a disk 25 which is designed to be rotated continuously by any suitable mechanism. A similar recording device 26 is provided with 110

a disk 27 which is also rotated continuously. The latter disk is designed to be engaged by a marking device 28, which is secured to a lever 29 pivoted at 30. This lever may be 5 shifted by a link 31 pivotally secured at 32 to a disk or plate 33 having a handle 34. The plate 33 is pivoted at its center. The lever 30 is provided with an anti-friction wheel or roller 35 arranged to bear on the 10 armature. When the handle 34 is turned in the direction shown by the arrow in Fig. 1 the roller will be brought up against the armature and the marking point 28 will be brought against the rotatable disk 27. It 15 will be understood that any other suitable means for simultaneously moving the armature 6 and recording the time of such movement may be substituted for the mechanism just described without departing in 20 the least from the spirit and the scope of this invention. The view herein shown is intended to be purely diagrammatic.

The magnet 20 is provided with an armature 36 which is pivoted at 37 and is 25 arranged to engage a contact 38. It has a depending rod 39 which is provided with two beveled stops 40 and 41 respectively. The lower end of the rod 39 constitutes a 30 marking device arranged to engage the disk 25. A conducting lever 42 is pivotally mounted at 43 and its end is arranged to engage the stop 40 to lift the rod 39. The stop 41 is arranged to engage a projecting portion 44 of the armature 45 of the 35 magnet 22 so as to force the armature toward the magnet against the tension of the spring 46.

The magnet 21 is provided with an armature 47 which is held by a spring 48 normally away from the magnet. The armature 47 is provided with a stem 49 arranged to enter recesses 50 in a rotatable locking disk 51. The end of the lever 42 is also arranged to enter the recesses 50. A handle 52 is provided for turning the disk 51. These 45 parts are shown diagrammatically since it is obvious that any other suitable mechanism for accomplishing the same purpose might fulfil the objects of the invention.

At 53 I have shown a governor arranged 50 to open or close a switch 54. This can only occur when the train stops. As long as the train is in motion the governor is up and the switch 54 is open. The magnet 23 is provided with an armature 55 arranged to 55 engage a contact 56.

Disposed at intervals along the track are short lengths of conducting rails 57. These rails are arranged to be engaged by the contact members 58 and 59. In the figures I 60 have illustrated them as brushes, but other forms of suitable contacts may be used. Each of the rails is connected with a switch 60, one side of which is grounded. The latter may be operated by the semaphore 61. 65 One of these third rail conductors 57 is asso-

ciated with each signal. The main track rails are shown at 62 and the wheels of the engine at 63.

From the foregoing description of the various parts of the device the operation 70 thereof may be readily understood. Let us assume that the train is running on a track not in sight of a signal. The brushes or contacts 58 and 59 are therefore not in engagement with the third rail sections since 75 these latter are only provided at the points where the signals are located. Each train is provided with a source of continuous current such as that shown at G. Current will now flow from this generator or battery 80 through the conductor 64, magnet 21, 65, 38, 36, (the latter being held up by means of the lever 42) 37, magnet 20, 66, lamp 67, magnet 7, 68, 56, armature 55, 69 and 70, back to generator. This circuit will energize the magnet 21, thereby holding the stem 85 49 of the armature 47 in a slot 50 of the disk 51, thereby locking this disk in position. This circuit will also energize the magnet 20, which tends to attract the armature 36. 90 The energization of the magnet 7 will cause the armature 6 to hold the valve 4 in position to effect communication between the pipes 1 and 9, thereby permitting the fluid pressure from the reservoir to force the 95 brakes away from the wheels and to open the steam pipe leading to the throttle in the manner already explained. The armature 55 is down on its contact 56, because the circuit through the magnet 23 is broken at the 100 brushes 58 and 59 which, as stated, are not now in contact with the rail 57. This condition will be maintained until the train is passing a signal. Suppose the signal which the train is passing is at clear, as shown in 105 Fig. 1. The switch 60 is closed and therefore the rail 57 is grounded. When the contacts 58 and 59 reach the rail 57 a circuit will be closed through the magnet 23. This circuit is as follows: from generator through 110 64, 71, 23, 72, 58, 57, 59, 73 and 70 back to generator. The armature 55 will be attracted, thereby breaking part of the circuit at 56, but the magnets 7, 20 and 21 will still receive current from the generator, since a 115 circuit will be completed from the positive side of the generator as described to the wire 68, thence by the conductor 74 through the wheel 63 and rail 62 to the ground, through the grounded conductor 75, resistance 76, conductor 77, switch 60, 78, rail 57, brush 59, conductors 73 and 70, back to generator. Since the circuits of the magnet 7, 20 and 21 are maintained the train will be permitted 120 to proceed when the semaphore 61 is in the position to indicate a clear track.

In Fig. 2 the semaphore is set at danger and the swinging of the semaphore into its danger position opens the switch 60. Now when the brushes 58 and 59 engage the short 125

rail 57 the circuit just traced through the wheels of the engine will be broken at 60, and since the circuit through the magnet 23 is complete the armature 55 will move from the contact 56, thereby breaking the actuating circuits of the magnets 7, 20 and 21. The deenergization of the magnet 7 will cause its armature to move away, thereby shifting the valve 4 so as to cut off communication between the pipes 1 and 9 and also permitting the latter to discharge into the atmosphere in the manner already described. This will cause a setting of the brakes and it will cause the closing of the valve 17 under the action of the spring 15 so as to shut off the steam in the pipe 19 leading to the throttle.

The deenergization of the magnet 21 will cause the locking stem 49, which is connected to the armature 47, to be drawn upwardly by means of the spring 48, thereby releasing the disk 51. The lever 42 is therefore free to turn on its pivot. The deenergization of the magnet 20 causes a downward movement of its armature 36 and also of the rod 39. The cam stop 41 pushes aside the extension 44 of the armature 45 which immediately springs in behind it, thereby locking it in its position. The lower portion of the rod 39 engages the rotating disk 25 and records the time at which the magnet 20 is deenergized. The downward movement of one end of the lever 42 brings the contacts 79 and 80 into engagement. It will be understood that the operating mechanism, *i. e.*, the magnets, armatures, recording devices, and locking devices are inclosed in a casing where the engineer cannot get at them. It is only when the train is brought to a full stop that he can again proceed, and this is accomplished through the medium of the governor 53. As long as the train is in motion this governor is up, as shown in Fig. 1, and the switch 54 is open, but when the train stops the governor closes the switch 54 and a circuit is established as follows: from the generator G through 64, 81, lever 42, contacts 79 and 80, 82, magnet 22, 83, governor 53, switch 54, 84 and 70 to generator. The magnet 22 is thereby energized but since the locking stem 49 is up, the disk 51 may be rotated by means of the handle 52 in the direction shown by the arrow in Fig. 2 so as to force the rod 39 upwardly, thereby bringing the armature 36 against the contact 38. The third rail sections 57 are of such a length that the brushes pass off the rail in the time that it takes the train to stop from the momentum gained. In other words, the contact of the brushes 58 and 59 with the rail section is a relatively short one, entirely sufficient to energize the magnet 23, but not sufficient to bring the train to a stop before the brushes leave the rail.

Therefore when the engineer lifts the armature 36 of the magnet 20 by means of the disk 51 as described the energizing circuit of the magnets 7, 20 and 21, which has already been described, is again completed. 70 Pressure is therefore admitted from the pipe 1 to the pipe 9 releasing the brakes and permitting the steam to flow to the throttle past the valve 17. The locking stem 49 of the armature 47 of the magnet 21 is brought 75 into position to lock the disk 51. The circuit of the magnet 22 is broken at 79 and 80 and when the train starts up again the governor 53 opens the switch 54. When the circuit is first broken through the magnets 7, 20 and 21, the lamp 67, which is glowing normally when the current is flowing, goes out, and this serves as an additional danger signal to the engineer. When the circuit is again established it is lighted. 80 In order to give the engineer control of the train under extraordinary circumstances I provide means for manually lifting the armature 6. Thus it will be seen that if the disk 33 is rotated in the direction shown 85 by the arrow in Fig. 1 the roller 35 will be forced upwardly, thereby moving the armature 6 and forcing the valve 4 into position so as to establish communication between the pipes 1 and 9. The movement of the lever 29 will cause the marking member 28 to engage the rotating disk 27 so that if this manual means is used the precise time at which it is used is recorded on the recording device 26. As stated before, any other means for accomplishing the same purpose of raising the armature and simultaneously recording the time of movement of the armature might be used in lieu of the arrangement shown. A modification of this 90 arrangement is shown in Fig. 3. In this figure additional conducting members 86 are provided along the track. These conducting members are normally grounded through the armature 87 of a magnet 88. The energizing circuit of the magnet 88 is from the battery B, or other source of current at the train dispatcher's office through 91, key K', K² or K³ and by the conductors 90, 90^x or 90^y through the respective magnets 88, 88^x or 88^y. Since these conductors 95 are normally grounded, then the train can proceed, but in case the ground should be broken, as it may be from the train dispatcher's office by pressing one of the buttons K', K² or K³ respectively, then the train will be stopped in the manner already indicated on that particular section from which the ground has been removed. 100

It will thus be seen that with this arrangement the train dispatcher has under his control the stopping of a train automatically at any particular section or block along the line where he wishes such train to stop. Immediately on the release of the 105 110 115 120 125 130 135

key the conductor 86 is again grounded and the train may proceed. It is obvious that these conducting rails 86 may be used or not as desirable without interfering in any way 5 with the automatic train stopping mechanism as described above.

I claim:—

1. In an automatic train stopping device, the combination with a pressure pipe, of 10 brake setting means controlled thereby, a valve controlled by said pressure pipe for cutting off steam from the throttle, electro-magnetic means for controlling the pressure in the pressure pipe, means carried by the 15 engine for energizing said electro-magnetic means, means for automatically deenergizing said electro-magnetic means, said last named means comprising a relay having contacts disposed in the circuit of the electro- 20 magnetic means, a pair of contacts in circuit with said relay, and conductors disposed along the track for bridging the contacts and thereby energizing the relay.
2. In an automatic train stopping device, 25 the combination with a pressure pipe, of brake setting means controlled thereby, a valve controlled by said pressure pipe for cutting off steam from the throttle, electro-magnetic means for controlling the pressure 30 in the pressure pipe, means carried by the engine for energizing said electro-magnetic means, means for automatically deenergizing said electro-magnetic means, said last named means comprising a relay having contacts 35 disposed in the circuit of the electro-magnetic means, a pair of contacts in circuit with said relay, one of said contacts having electrical connections with one side of said electromagnetic means, the other 40 side of said electromagnetic means being permanently grounded, conductors disposed along the track for bridging the contacts and thereby energizing the relay, said conductors being normally grounded, and 45 means for breaking the ground connection of any of said conductors.
3. In an electrical train stopping system, a fluid pressure pipe, a valve for controlling the fluid pressure, electro-magnetic means 50 for controlling the valve, a source of current, a normally closed circuit connecting said source of current and said electro-magnetic controlling means, a relay for breaking the circuit of the electro-magnetic controlling 55 means at a point on one side of said source of current, and means on the opposite side of said source of current and controlled by the normally closed circuit for breaking the circuit through the electro-magnetic controlling means, at another 60 point.
4. In an electrical train stopping system, a fluid pressure pipe, a valve for controlling the fluid pressure, electro-magnetic means 65 for controlling the valve, a source of cur-

rent, normally closed connections between said source of current and said electro-magnetic controlling means, a relay for breaking the circuit of the electro-magnetic controlling means on one side of said source of current, and means on the opposite side of said source of current for breaking the circuit at another point through the electro-magnetic controlling means, said last named means comprising a magnet having its winding and its armature in series with the electro-magnetic controlling means.

5. In a train stopping device, a pressure pipe, means for controlling the pressure of motive fluid in said pressure pipe, a normally closed circuit including a source of current, and an electro-magnet for operating said controlling means, a cut out relay having its contacts in series with the winding of said electro-magnet for breaking the circuit through said electro-magnet, means in said normally closed circuit for breaking the circuit through the electro-magnet at another point, and a normally open circuit including the energizing coils of the cut out relay.

6. In a train stopping device, a pressure pipe, means for controlling the pressure of motive fluid in said pressure pipe, a normally closed circuit including a source of current, and an electro-magnet for operating said controlling means, a cut out relay having its contacts in series with the winding of said electro-magnet for breaking the circuit through said electro-magnet, means in said normally closed circuit for breaking the circuit through the electro-magnet at another point, and a normally open circuit, including the energizing coils of the cut out relay.

7. In a train stopping device, a pressure pipe, means for controlling the pressure of motive fluid in said pressure pipe, a normally closed circuit including a source of current, and an electro-magnet for operating said controlling means, a cut out relay having its contacts in series with the winding of said electro-magnet for breaking the circuit through said electro-magnet, means in said normally closed circuit for breaking the circuit through the electro-magnet at another point, and a normally open circuit, including the energizing coils of the cut out relay.

8. In a train stopping mechanism, a pressure pipe, electro-magnetic means for controlling the pressure in said pressure pipe, a source of current for energizing said electro-magnetic means, a recording magnet, a pair of contacts for said recording magnet, an armature for normally closing said contacts, the winding of said recording magnet, the armature and the contacts being in series with the winding of said electro-magnet, a recording disk, and a marking device con- 13

nected with the armature of said recording magnet and arranged to engage the recording disk when the recording magnet is de-energized.

9. In a train stopping mechanism, a pressure pipe, electro-magnetic means for controlling the pressure in said pressure pipe, a source of current for energizing said electro-magnetic means, a recording magnet, a pair of contacts for said recording magnet, an armature for normally closing said contacts, the winding of said recording magnet, the armature and the contacts being in series with the winding of said electro-magnet, a recording disk, a marking device connected with the armature of said recording magnet and arranged to engage the recording disk when the recording magnet is de-energized, and a locking device for normally preventing the return of the marking device from the recording disk.

10. In a train stopping mechanism, a pressure pipe, electro-magnetic means for controlling the pressure in said pressure pipe, a source of current for energizing said electro-magnetic means, a recording magnet, a pair of contacts for said recording magnet, an armature for normally closing said contacts, the winding of said recording magnet, the armature and the contacts being in series with the winding of said electro-magnet, a recording disk, a marking device connected with the armature of said recording magnet and arranged to engage the recording disk when the recording magnet is de-energized, a locking device for normally preventing the return of the marking device from the recording disk, and electro-magnetic means for releasing the locking device to permit its return to normal position.

11. In a train stopping mechanism, a pressure pipe, electro-magnetic means for controlling the pressure in said pressure pipe, a source of current for energizing said electro-magnetic means, a recording magnet, a pair of contacts for said recording magnet, an armature for normally closing said contacts, the winding of said recording magnet, the armature and the contacts being in series with the winding of said electro-magnet, a recording disk, a marking device connected with the armature of said recording magnet and arranged to engage the recording disk when the recording magnet is de-energized, a locking device for normally preventing the return of the marking device from the recording disk, electro-magnetic means for releasing the locking device to permit its return to normal position, and a governing device dependent upon the speed of the train for controlling the circuit through the last named electro-magnetic device.

12. In a train stopping mechanism, a pressure pipe, electro-magnetic means for controlling the pressure in said pressure pipe, a

source of current for energizing said electro-magnetic means, a recording magnet, a pair of contacts for said recording magnet, an armature for normally closing said contacts, the winding of said recording magnet, the armature and the contacts being in series with the winding of said electro-magnetic, a recording disk, a marking device connected with the armature of said recording magnet and arranged to engage the recording disk when the recording magnet is de-energized, a locking device for normally preventing the return of the marking device from the recording disk, electro-magnetic means for releasing the locking device to permit its return to normal position, a governing device dependent upon the speed of the train for controlling the circuit through the last named electro-magnetic device, and manual means for raising said marking device, said manual means being normally locked.

13. In a train stopping mechanism, a pressure pipe, electro-magnetic means for controlling the pressure in said pressure pipe, a source of current for energizing said electro-magnetic means, a recording magnet, a pair of contacts for said recording magnet, an armature for normally closing said contacts, the winding of said recording magnet, the armature and the contacts being in series with the winding of said electro-magnet, a recording disk, a marking device connected with the armature of said recording magnet and arranged to engage the recording disk when the recording magnet is de-energized, a locking device for normally preventing the return of the marking device from the recording disk, electro-magnetic means for releasing the locking device to permit its return to normal position, a governing device dependent upon the speed of the train for controlling the circuit through the last named electro-magnetic device, manual means for raising said marking device, said manual means being normally locked, and electro-magnetic means for releasing the locking device of said manual operating means.

14. In a train stopping mechanism, a pressure pipe, electro-magnetic means for controlling the pressure in said pressure pipe, a source of current for energizing said electro-magnetic means, a recording magnet, a pair of contacts for said recording magnet, an armature for normally closing said contacts, the winding of said recording magnet, the armature and the contacts being in series with the winding of said electro-magnet, a recording disk, a marking device connected with the armature of said recording magnet and arranged to engage the recording disk when the recording magnet is de-energized, a locking device for normally preventing the return of the marking device from the recording disk, electro-magnetic means for re-
